RAZOR BLADE PLANE

Arthur W. Miltenburg, Milwaukee, Wis.

Application January 9, 1947, Serial No. 721,096

1 Claim. (Cl. 145—5)

1

My invention relates to improvements in blade holders for planes, chisels and the like.

The object of my invention is to provide means whereby a razor blade or equivalent thin, resilient cutting element may be securely clamped to a holding plate adapted to serve as the blade holder of a plane, or as the handle of a chisel.

In the following description reference is had to the accompanying drawings, in which

Figure 1 is a plan view of a plane body of my invention, with the blade holder partially broken away.

Figure 2 is a sectional view drawn to line 2—2 of Figure 1.

Figure 3 is a detail view of the upper surface of the blade holding plate.

Figure 4 is a view of the under surface of said plate.

Figure 5 is an enlarged fragmentary sectional view of a holder and blade drawn to a modification of plane shown in Figure 2.

Like parts are identified by the same reference characters throughout the several views.

A thin steel shaving blade, preferably of the safety razor blade type shown at 10 in Figure 2, is clamped to the under surface of one end portion of a flat handle like holder 11. The latter is recessed at 12 and the end portion of the blade distant from its cutting edge 13 is closely fitted to this recess and held therein by a clamping plate 14 also fitted to an extension 15 of the recess 12 in which it is held by a bolt 16 extending through the plate 14 and the holder 11 for threaded engagement with a thumb nut 17 on the exposed or upper side of the plate. When the nut is turned to clamping position, the head 18 of the bolt draws the plate 14 toward the holder and forces the engaged portion of the blade into the recess 12 to securely clamp it to the holder. If the blade has a thick back as indicated at 20, the recess 12 is deepened to receive it and the contour of the under surface 22 of the end portion of the holder determines the position of the blade cutting edge relative to the holder.

The blade shown in Figure 2 may be assumed to be a safety razor blade of a well known type having but one cutting edge 13.

In Figure 5 a blade 26 is illustrated which is thin throughout its length and apertured at 27, whereby a correspondingly apertured clamping plate 28 may be used to bind it to the holder. In this construction one or more bolts 29 extend through the plate 28, the holes 27 in the blade 26 and through the holder to receive the thumb nuts 30.

If desired, the lower marginal portion 31 of the plate 28 may be given a slight upward curve and the under surface 32 of the lower end portion of the holder may be correspondingly curved whereby when the clamping pressure is applied by the thumb nuts the blade will be flexed and the position of its cutting edge relative to the holder and clamping plate edges precisely determined. In Figure 2 and also in Figure 5 the cutting edge of the blade is preferably ground to a one way bevel.

In either case, the holder, blade and clamping means constitute a unit which may be separately used as a chisel-like tool, or may be secured to the body of a plane in the manner now to be described.

As usual in smoothing planes the stock or body has a rectangular bottom portion 40 provided with a transverse slot 41, and an upwardly extending rear portion or bed 42, which serves as a holder support, and the front face 43 of which has a downward and forward inclination to the slot 41. The holder 11 may be secured to the upper portion of this surface by a screw 44 which passes through a key hole slot 43' in the holder. The head of the screw has a diameter greater than the narrow portion of the slot, but less than its larger portion, and the slot is so located, and its narrow portion is of such length that the cutting edge of the blade may be adjusted precisely to a cutting position of projection through the slot 41.

As best shown in Fig. 5, the slanting portion of the plane stock 40 to the immediate rear of the transverse slot 41, hereinafter referred to as the slot back or blade support, provides a blade supporting surface 35 deviating from the projected inclined plane of the holder support or bed 42 upon which rests the holder 11 which mounts the blade 26. As best shown in Figs. 1, 2 and 5 the forward edge 36 of the holder 11, in normal adjusted position, overlaps the upper edge of the blade support 35 whereby to firmly hold the thin blade 26 flexed against the blade support 35. The lap of the holder edge over the blade support also acts to firmly seat the thin blade against the blade support to prevent chatter and the like.

The slot 41 is flanked by side flanges 46 which connect the front and rear portions of the body. The inclined face 43 of the plane body is recessed at 47 to receive the clamping plate 28. Otherwise the surface 43 may conform to that of the holder and the blade against which it bears. In Figure 2 the surface 43 is similarly recessed to

receive the clamping plate 14. The plane body and the holding plate 11, when combined, constitute a holder for blades of the general type shown in Figures 2 and 5.

I claim:

In a razor blade plane, the combination with a stock having a transverse slot opening to its lower face and having a transversely channelled bed portion comprising upper and lower surfaces separated by the channel and inclined toward the slot, a blade holder comprising an apertured plate spanning the slot and provided with a downwardly opening transversely extending channel with a step and a deeper portion opposite the channel of said bed portion, a screw extending through the aperture of the plate and threaded into the stock to clamp the plate to the stock, a clamping jaw disposed within said bed portion channel and having a rear margin seated upon the step of the plate within its said channel and a forward margin underlapping the deeper portion of said downwardly opening plate channel, a threaded bolt connected with said jaw and projecting upwardly through said plate, a wing

nut on the bolt and bearing on said plate, and a razor blade resting on the lower surface of the bed portion with its edge projecting through the slot of the stock, said blade having a back along its upper margin disposed in part in each of the channels of the bed portion and plate and clamped to the plate by said jaw and having an intermediate portion clamped by the plate to said lower bed portion surface.

10
